UNITED STATES PATENT OFFICE.

DANIEL L. CHANDLER, OF AYER, MASSACHUSETTS.

TOOL-FEED MECHANISM FOR METAL-WORKING MACHINES.

No. 836,631.

Specification of Letters Patent.

Patented Nov. 20, 1906.

Original application filed April 14, 1904, Serial No. 203,145. Divided and this application filed June 29, 1906. Serial No. 267,534.

To all whom it may concern:

Be it known that I, DANIEL L. CHANDLER, of Ayer, in the county of Middlesex and State of Massachusetts, have invented certain new and useful Improvements in Tool-Feed Mechanisms for Metal-Working Machines, of which the following is a specification.

This invention relates to feeding mechanisms for the cutting-tools of metal-working machines, particularly planing-machines, and is a division of a pending application filed by me April 14, 1904, Serial No. 203,145, for planer.

The invention consists in a feeding mechanism of the character above stated, and has for its object to provide an improved mechanism by which the operator may quickly adjust the tool by hand when necessary, particularly in "backing out," or moving the tool in a direction contrary to the feed, and may vary the amount of feed of the tool while the machine is running. The application for which this mechanism is more particularly adapted is for feeding the tool of a planer either across the machine vertically or in any other direction, but especially for furnishing the cross-feed, and in the following description and the drawings accompanying the same it is shown as applied to such a machine; but it is not limited to such use and may be employed in connection with any machine performing a series of identical operations, whether continuously or intermittently, in which the tool must be advanced step by step.

Of the drawings, Figure 1 represents a side elevation of the feed mechanism embodying my invention as applied to a metal-planing machine, the view showing as much of such a machine as is necessary to illustrate the application of the invention. Fig. 2 represents a transverse vertical section of the planing-machine, showing the feed mechanism in front elevation. Fig. 3 represents an enlarged end elevation, showing the feed mechanism in detail. Fig. 4 represents an axial section of said mechanism. Fig. 5 represents an enlarged end elevation of the friction device for operating said feed mechanism from a shaft of the machine to which it is applied. Fig. 6 represents an axial section of the friction device.

The same reference characters indicate the same parts in all the figures.

In the drawings, 20 is the reciprocating platen of a planing-machine, to which the mechanism constituting my invention is applied, adapted to hold the work and mounted on the usual guide. Said platen is driven by a main drive-shaft 21, having a pinion 22 meshing with a gear 23 on the left-hand side of the planer-bed, said gear being attached to a counter-shaft 24, having a pinion 25 meshing with a gear 26, supported in bearings mounted on the machine-frame, which engages a rack 27, Fig. 2, on the under side of the platen.

The shaft 21 carries a fast driving-pulley 28, loose pulleys 29 30, and another fast pulley 31, flanked by a loose pulley 32. The respective pulleys receive motion from the belts 33 34 35, which imparts the forward or cutting stroke to the platen, a slow-return movement to the platen at the beginning and end of the non-cutting stroke, and a quick-return movement to the platen during the remainder of this stroke by engagement with the various pulleys at the proper times, such engagement being effected by belt-shifters 36 37 44, controlling the several belts and operated through 75 cam 42, link 49, and trip-lever 50, pivoted to the planer-bed 51 by suitable dogs carried by supports 56 60, mounted on the platen.

71 is the cross-feed saddle carrying the cutting-tool 72 and fed by a screw 73, journaled 85 in the vertically-adjustable beam 74 and operating in a nut on the cutter-saddle in the usual manner.

The mechanism by which the screw 73 is operated step by step by the driving mechanism to feed the saddle and tool constitutes the substance of the present invention and is constructed and arranged as follows:

On the end of screw 73 is a pinion 75, meshing with a gear 76, to which is fixed a toothed ratchet-wheel 77, as best seen in Figs. 3 and 4. Heretofore this ratchet-wheel has usually been fed step by step by an ordinary pawl yieldingly in contact with the ratchet. With such a construction when it becomes necessary to "back out" the tool 72 by hand—that is, move it in a direction contrary to the feed—by fitting a crank to the squared end of the screw 73 the operator has

been required to lift the pawl and rotate the crank and screw, the operation being a somewhat difficult and time-consuming one and usually requiring the operator's two hands to 5 perform it; but by the improved construction now to be described I avoid the difficult operation heretofore required and allow the power feed to be released and the tool backed out with one hand. On the sleeve 78, to which 10 the gear 76 and ratchet 77 are fixed, is mounted a pawl-support 79, having a split hub 80 frictionally embracing the sleeve.

81, Fig. 1, is the usual cross-feed rack operated by link 82, lever 83, and link 84 on a 15 wrist 85 on the friction-collar 86, embracing a drum 87 on the shaft 24. The rack 81 meshes with a pinion 88, Fig. 4, on a short shaft 89, carried by the beam 74. On the outer end of this shaft is affixed an arm or 20 finger 90, adapted to engage heels or projections 91 on the shafts of two oppositely-acting pawls 92, pivoted to the friction-support 79. These pawls have substantially radial noses engaging the teeth of ratchet 77 and 25 are provided with projections 93, connected by a spring 94, which tends to throw the pawls out of engagement with the teeth of the ratchet. Eccentrics 95 are provided for 30 disabling either pawl and allowing the other pawl 35 to feed the tool in the direction desired. The rack 81, receiving motion from friction-collar 86, oscillates the finger 90, which engages the operative pawl and throws it into engagement with the ratchet 77 and feeds said ratchet a distance depending upon the length 40 of stroke of the rack, the friction of support 79 on collar 78 being such as to permit this action to take place. On the back stroke of finger 90 it encounters the heel-piece 91 of the 45 operative pawl and relieves the strain on the operative pawl, whereupon the spring 94 retracts the latter from engagement with ratchet 77, and the support 79 is retracted for a fresh operative stroke.

50 It will be seen that the operative pawl 92 is under strain only at the moment of feed. This strain may be relieved at any time it is desired by the operator to feed by hand by applying the hand-crank to screw 73 and giving the latter a slight "kick" ahead merely sufficient to relieve the friction between ratchet 77 and pawl 92, whereupon the pawl will be automatically released from engagement with the ratchet by the action of its spring 94, and the tool will be thereby freed from the 55 automatic feed and may be fed by hand in either direction. Inertia and recoil will also in most cases be sufficient to relieve the pawl immediately after its feeding movement.

60 96 is a shaft on beam 74, splined to gearing in the saddle 71 in the usual manner, whereby a vertical feed is imparted to the tool 72 upon removing the pinion 75 and substituting a pinion on shaft 96 to mesh with gear 76. It

will be understood, therefore, that my improvement applies to the vertical or other feed of the tool as well as to the horizontal feed thereof.

65 The friction of collar 86 on its drum 87 is furnished by a spring 98, Fig. 5. The collar 70 is opened at each end of its stroke to relieve this friction by a cam-strut 99, operating between the limbs of the collar and having an arm 100 alternately engaging two pins 101 75 102 as the drum is oscillated to and fro by the reversed movements of shaft 24. I mount the pin 102 upon a hand-lever 103, adjustable about the axis of shaft 24 and having a locking-pin 104 at its upper end adapted to engage any one of a segment of 80 holes 105 105, formed in the side of the planer-bed. By the foregoing arrangement while the planer is running the operator may adjust the stroke of rack 81, and hence the length of the cross-feed movement at each 85 reciprocation of the planer-platen from nothing to a maximum by swinging the lever 103 so as to bring its pin 102 nearer to or farther from the fixed pin 101.

90 I do not broadly claim the friction-box automatically opened by stationary abutments, since heretofore it has been a common practice to provide such a box equipped with a wrist-pin of adjustable radial position, but such construction made it necessary or 95 desirable to stop the planer whenever a new adjustment was to be obtained, thereby causing loss of more or less time. It will be seen that my invention saves much time over such a device.

99 It is obvious that the pawl-and-ratchet mechanism and the rack 81 might be applied to a machine other than a planer and connected to a shaft which rotates wholly in one direction instead of to one which oscillates as 105 does that here shown, for the link 84 is adapted to produce reciprocation in the rack equally as well when connected to a crank on such a shaft as to a vibrating arm. I desire it to be understood, therefore, that my invention is applicable to a wide variety of machines and is not limited in its use to any particular one.

100 I claim—

110 1. The combination of a tool-holder, a rotary feeding member movable step by step to advance said holder, a feeding element for rotating said member, yielding means tending to hold said element retracted from operative relation with the member, and a separate driver movable relatively to the element to engage and place the same in operative relation with the member and then advance the element and member.

115 2. The combination of a tool-holder, a ratchet to feed the same, a pawl having a movement relatively to the ratchet to engage the same and a further movement to feed,

- and a separately-reciprocable driver having provisions to engage and impart such movements in succession to the pawl, and yielding means holding the pawl free of the ratchet when free from engagement by the driver.
3. The combination of a tool-holder, a ratchet to feed the same, a pawl having ratchet-engaging and ratchet-feeding movements, yielding means normally holding said pawl retracted, an oscillatory driver adapted to successively impart said movements to the pawl, and a support for said pawl independent of the driver and having a frictional connection with the ratchet.
4. The combination of a tool-holder, a rotary member having a step-by-step motion for imparting feed movement to said holder, a feeding element, yielding means holding said element, normally retracted from operative position for rotating said member, means to move said element into operative position and feed said member, and a disabling device for said feeding element adapted to hold the same out of operative position and resist the action of said means.
5. The combination of a tool-holder, a driver movable in opposite directions, and a plurality of feeding elements intermediate the driver and tool-holder and arranged to be alternately engaged by the driver in its opposite movements, said elements being connectable with the tool-holder and movable to feed the latter when engaged by the driver, and each adapted to be independently restrained from connection with the holder, and means for so restraining the feeding elements, whereby the driver in its opposite movements is enabled to advance the holder intermittently.
6. The combination of a tool-holder, a driver movable in opposite directions, a plurality of feeding elements mounted independently of the driver intermediate the driver and tool-holder and arranged to be alternately engaged by the driver in its opposite movements, said elements being connectable with the tool-holder and movable to feed the latter when engaged by the driver, and disabling devices for independently restraining either element from connection with the holder, whereby the feeding elements may be alternately operated by the driver in its opposite movements for connection of one of them at different points with the tool-holder to feed the latter.
7. The combination of a tool-holder, a ratchet to feed the same, a plurality of oppositely-arranged pawls for engaging and feeding the ratchet, yielding means connected to said pawls tending to retain them out of operative relation to the ratchet, a driver independent of said pawls and arranged between them, movable in opposite directions to engage said pawls alternately, and connect one of them with the ratchet, and a disabling device for one of the pawls.
8. The combination of a tool-holder, a driver alternately movable in opposite directions, a plurality of feeding elements intermediate the tool-holder and driver arranged to be alternately engaged by the driver in its opposite movements and one of them operated for connection with the tool-holder, positive means arranged to be independently operated to retain either of said feeding elements out of operative connection with the tool-holder, and yielding means tending always to hold the feeding elements out of such connection.
9. The combination of a tool-holder, a ratchet for feeding the same, a pawl-holder, oppositely-arranged pawls on said holder adapted to engage and feed the ratchet, yielding means connected to said pawls tending to retain them out of engagement with the ratchet, a driver movable in opposite directions and having a projection between the pawls for engaging them alternately, and an independent positive disabling device for each pawl adapted to retain the respective pawl out of connection with the ratchet.
10. The combination of a tool-holder, a ratchet for feeding the same, a pawl-holder, oppositely-arranged pawls on said holder adapted to engage and feed the ratchet, yielding means connected to said pawls tending to retain them out of engagement with the ratchet, independent positive disabling devices for the pawls adapted to be adjusted to hold one of the pawls out of operative relation with the ratchet, rendering said pawl inactive, the other pawl remaining active, and a driver movable in opposite directions arranged to engage said pawls alternately, to move the pawl-holder in opposite directions and periodically connect the active pawl with the ratchet.
11. The combination of a tool-holder, a ratchet to feed the same, a pawl-holder movable about the axis of the ratchet, oppositely-arranged pawls pivoted to the pawl-holder for engaging and feeding the ratchet and each having a projection, a spring connecting said projections and tending to hold the pawls out of engagement with the ratchet, an oscillatory driver having an arm projecting between said pawls and adapted to engage the projections thereof alternately, to move the pawls into engagement with, and thereafter feed the ratchet, and an independent positive device mounted adjacent each pawl adapted to be engaged therewith and to retain said pawl out of engagement with the ratchet.
12. The combination of a tool-holder, a reversely-rotating shaft having a friction-drum, a friction-collar on said drum, a trip device for relieving the friction of said collar, abutments for engaging said trip device at

opposite ends of its stroke, an arm carrying one of said abutments, and means for fixing said arm in a variety of angular positions, whereby its abutment is located at different distances from the other abutment.

13. The combination of a tool-holder, a reversely-rotating shaft having a friction-drum, a friction-collar on said drum, a trip device for relieving the friction of said collar, abutments for engaging said trip device at opposite ends of its stroke, and a member

carrying one of said abutments movable into a variety of different positions, whereby the distance between the abutments may be varied to adjust the amount of travel of the drum.

In testimony whereof I have affixed my signature in presence of two witnesses.

DANIEL L. CHANDLER.
